441/129FIG. 1 is a perspective view of an inflatable recreational tube;
FIG. 2 is an enlarged view of the area of FIG. 1 within a chain dotted circle;
FIG. 3 is a top plan view of the inflatable recreational tube shown in FIG. 1;
FIG. 4 is a bottom plan view of the inflatable recreational tube in FIG. 1;
FIG. 5 is a left elevational view of the inflatable recreational tube shown in FIG. 1;
FIG. 6 is a right elevational view of the inflatable recreational tube shown in FIG. 1;
FIG. 7 is a front elevational view of inflatable recreational tube shown in FIG. 1;
FIG. 8 is a rear elevational view of inflatable recreational tube shown in FIG. 1;
FIG. 9 is cross-sectional view along line 9-9 in FIG. 3; and,
FIG. 10 is cross-sectional view along line 10-10 in FIG. 3.
The portions of the figures shown in broken lines represent an area of the design being highlighted for an enlarged view.**1 Claim, 7 Drawing Sheets**(56)
